PARTITION AND POST CONSTRUCTION

Filed March 1, 1930

UNITED STATES PATENT OFFICE

SAMUEL SMILEY, JR., OF CINCINNATI, OHIO, ASSIGNOR TO THE GLOBE-WERNICKE COMPANY, OF NORWOOD, OHIO, A CORPORATION OF OHIO

PARTITION AND POST CONSTRUCTION

Application filed March 1, 1930. Serial No. 432,437.

This invention relates to a partition or wall construction and is particularly directed to the fabrication of a sectional post or a pilaster for joining sections of a partition. 5 The sections of the post or pilaster are similar to those disclosed and claimed in the copending application Serial No. 333,588, filed January 19, 1929, the invention in the present instance residing in improved devices for 10 connecting and locking the sections together and spacing them as well as the cooperative construction of the post sections in combination with the locking devices.

It is, therefore, an object of this invention 15 to provide efficient and conveniently applied spacing and connecting devices for joining the sections of a pilaster or post and to provide that these devices may be inserted into position between the set-up and spaced sections of the post at any point along the length thereof and in any number.

Other objects and certain advantages will 20 be more fully set forth in a description of the following drawings in which:

25 Figure 1 is a sectional view taken vertically and longitudinally of the wall through a post or pilaster, illustrating the devices in position.

Figure 2 is a perspective view of a section 30 of a post or pilaster apart from the wall further detailing the manner of mounting the devices.

Figure 3 is a sectional view taken on line 3—3, Figure 1.

35 Figure 4 is a face view of one of the connecting and spacing devices showing it in insertable position prior to swinging movement of the spreader element thereof for locking the post sections together.

40 The post to which the improved clip and spacer devices are applied is fabricated of a pair of uprights or sections 5, 5 assembled in spaced relation. The placement along the post length and number of the connecting and spacing devices 6, is purely arbitrary depending on the arrangement required to 45 efficiently attach the sections.

The uprights or sections 5 of the post are 50 assembled in various ways. In some instances one section of a particular post is attached

to an assembled section of wall and the other to a second wall section. These wall sections, with the post uprights attached along their adjacent edges, are set up, in a channel floor strip 7 as shown, and brought together to space the posts approximately their assembly distance apart whereupon the connecting devices are inserted and applied. In other instances, the post is assembled as a unit apart from the wall by simply inserting the devices.

The devices 5 accomplish the appropriate spacing of the post uprights and the setting of the spacer means 8 in each instance interlocks the sections in a clip element 9. The condition of the post is extremely solid since the spacers act as struts throughout the length of the post. Once the struts or spreaders have been set, it is impossible to dislodge the clip and a sturdy durable connection is accomplished.

Panels 10 of the wall sections are suitably joined horizontally and draw pieces 11 extend interiorly of the horizontal seams, these draw pieces being slightly shorter in length than the horizontal extent of the panels, so that tightening of the hook bolts 12, hooked in the ends of the draw pieces and passing through apertures 13 in the sections or uprights of the post, by means of nuts 14 within the post draws the post sections firmly upon the vertical edges of the wall sections, (see Figure 1).

The means for joining the panels and the means for connecting the wall sections and post sections together are described and claimed in a copending application, Serial No. 427,777 filed February 12, 1930. For this reason the structure of the wall is not described in detail it being sufficient for the purposes of this invention to set forth that the respective post sections are capable of being attached along the adjacent edges of partition or wall sections.

Each section or upright 5 of the posts is of channel form generally. A longitudinal depression or groove 15 is formed in the outer face of each section. Inwardly turned flanges 16 are provided, extending from the side flanges or walls of the channel shaped up-

rights. The uprights of a post are disposed with the general channel forms thereof facing inwardly. The tying together or connecting of these uprights is accomplished by means 5 of the clips 9 of the devices 6 cooperating with the longitudinally and inwardly disposed flanges 16 which are adjacent in the assembled structure.

10 In order to securely interlock the sections or uprights together the clip has its engaging ends flanged outwardly and slightly inwardly toward each other to hook about the flanges 16 which are also slightly turned back relative to the respective channel shaped up- 15 rights of which they constitute a part.

As shown in Figure 3, elongated cover plates 18 are sprung into position over the space between the post sections, these plates having outwardly turned flanges slightly 20 turned back and away from each other to hook about and between the flanges 16.

The grooves or depressions in the faces of the channel uprights are of dovetail form whereby the side walls 19 thereof function to 25 receive the cover plates in the same manner as the correlated spaced flanges of the respective post sections the groove being the same width as the space. The cover plates are used entirely around the post when it 30 stands alone or are disposed on those sides which are not abutted by wall sections. The frames 20 of the wall section panels 10 are adapted to seat within the depressions or 35 grooves as illustrated in Figure 3.

To prevent inward movement of the post sections which would tend to loosen the clips 9 the spacer element or strut 8 is pivoted to the clip for spreading the sections on the clip. A pivot pin 21 is disposed centrally of both 40 clip and strut or spacer. The pivot pin is riveted into position in the clip as shown and has an extending stud portion passing through a longitudinal slot 22 in the spacer which stud terminates in a head 23. The 45 spacer is a flat piece generally and is adapted to be rotated on the set clip after the parts of the post are drawn together. The slot permits the spacer to shift on the clip longitudinally to accommodate for variation in 50 the depth of the channel shaped post sections. If a floating rotative connection such as the slotted structural provision were not made the bracing or spacing action might be entirely confined to one section and the opposite 55 end of the spacer unengaged and inoperative.

As shown in Figure 4 those corners 24 of the spacer plate edges adapted to primarily engage the inner walls of the respective post sections for spreading the same on the clip 60 as the spacer is rotated are rounded and inclined to a central point of the respective edges. The engagement of these edges with the post sections provides a camming action for easily spreading the sections. The spacer 65 plate for manipulation purposes is provided

with short lugs 25 formed inwardly and away from the clip from the upper and lower edges of the plate respectively and toward the opposite ends of the respective edges. These lugs or flanges may also be described as being toward those ends of the top and bottom edges which are not rounded being suitably positioned for rotating the plate anti-clockwise. The plates constituting the clip and spacer respectively lie flat against each other and are consequently braced. The operative edges of the spacer plates engage the post sections in the corners thereof at each side of the depressions.

The connecting and spacing devices 6 are readily and arbitrarily applied as needed and it is unnecessary to provide any attaching means on the post sections of any form other than the hook flanges. These longitudinal hook flanges of the post sections are continuous and the devices therefore applicable at any point.

Having described my invention, I claim:

1. In a device of the class described, a pair of spaced post sections providing opposing longitudinal hook edges, and locking and spacing devices, each comprising, a hook element disposed between and about the opposing hook edges of the sections and a spreading element pivoted to the hooking element and adapted to be swung into alignment with the hook element whereby its outer ends engage and spread the respective sections and firmly engage the hook in position.

2. In a post of the class described, a pair of spaced and facing channel uprights, said channel uprights having inwardly formed hook flanges disposed along the side flanges thereof, a clip for engaging the adjacent hook flanges for connecting the uprights, a spacer plate rotatably mounted on said clip, said plate having its diagonally opposite edges rounded for primarily engaging the uprights in cam action as the plate is rotated into aligned position relative to the clip and means for rotating said plate.

3. A device of the class described, comprising, a clip plate having hook flanges at its end edges, a spacer plate pivotally attached to the clip, said parts disposed flat against each other, and said spacer plate providing diagonally opposite rounded corners and means for rotating the spacer plate on the clip plate.

In witness whereof, I hereunto subscribe my name.

SAMUEL SMILEY, JR.
